SHOE

James C. Givren, Brockton, Mass.

Application October 28, 1938, Serial No. 237,429

2 Claims. (Cl. 36—12)

This invention relates to shoes which have an incorporated cushion filler.

Shoes in which cushions are disposed either between the soles or in the cavity between the overlasted margins of the upper have recently become popular and in demand. Since a cushion is more useful in the forepart of a shoe than elsewhere, many attempts have been made to replace the ordinary bottom filler with a resilient cushion material such as sponge rubber. However, shoes made in this fashion have not found favor for the reason that the cushion is located only in the central portion of the forepart and is bounded by a broad band of non-resilient materials consisting of the insole, the overlasted margin of the upper and the outsole. With this background in view, I have devised a method of shoemaking in which the insole is formed with a cavity in the forepart which extends nearly to the peripheral edge of the sole, being bounded by a very narrow marginal band. In assembling the shoe of my invention the recessed insole is placed upon a last, the cavity is filled, an upper is worked over the last, and its overlasted margin is secured to the narrow band or to the surface of the resilient filler. Subsequently a sole is secured to the lasted shoe. With a shoe so constructed a cushion is provided which extends beneath almost the entire forepart of the foot and is much more comfortable than shoes having a cushion located within the more restricted cavity bounded by the overlasted margin. The most important objects of my invention are to provide a cushion sole shoe which is more comfortable than shoes heretofore produced and which may be manufactured advantageously and in which the cushion is securely anchored in place and prevented from displacement in continued wear. To these ends an important feature of my invention resides in a resilient cushion disposed in the shoe bottom above the overlasted margin of the upper. A characteristic of my invention is the applying of the cushion filler to the insole prior to the lasting operation, and subsequently working the margin of the upper over the exposed surface of the filler.

These and other features of the invention will be best understood from the following description of a preferred embodiment thereof selected for purposes of illustration and shown in the accompanying drawing in which,

Fig. 1 is a fragmentary view in perspective showing the forepart of an insole used in my invention,

Fig. 2 is a view in perspective showing an insole applied to a last and having its cavity filled,

Fig. 3 is a view in perspective, partly in cross-section of the lasted shoe, and

Fig. 4 is a view in transverse cross-section of the completed shoe.

Fig. 5 is a view partly in perspective and partly in cross section showing alternative constructions.

The first step in my method is to pass an insole 10 of leather or other suitable material through a matrix splitting machine in order to form a large cavity in the forepart thereof, as shown in Fig. 1. 10 Where a leather insole is used, the cavity may be formed in the flesh side so that it is bottomed by a thin sheet 14 of grain leather. The narrow marginal band 12 of unreduced thickness is of width not exceeding the full thickness of the insole 15 and bounds the cavity thus formed. After the splitting operation has been performed, the insole is temporarily secured to a last 18 with its cavity exposed. Subsequently a filler of resilient cushioning material 16, for example a sponge rubber 20 pad or a mixture of ground cork and rubber, is placed in the cavity in such a way that the surface from one edge of the insole to the other across the forepart is smoothly rounded. An upper 20 is then worked over the last according to 25 ordinary shoemaking practice, and the overlasted margin is secured to the surface presented by the filled insole 10. In other words, the upper 20 is lasted over an appreciable area of the exposed surface of the cushioning material 16. The heel-seat portion of the overlasted margin is secured by heel-seat nails 26, the shank portion of the overlasted margin is herein shown as fastened with staples 24. The forepart of the overlasted margin is secured by cement to the narrow band 35 12 and to the surface of the resilient material 16. The upper 20 includes the outer covering as well as other elements such as a counter 30 and a lining. After the shoe has been thus lasted, the upper is trimmed to remove pleats and bunches, 40 a sole 22 is cemented to the bottom of the lasted shoe by ordinary methods, the last 18 is withdrawn and the shoe is then completed.

It will be apparent from an inspection of Fig. 4 that the resilient cushion filler 16 extends over 45 almost the entire forepart of the sole area of the shoe and only a narrow marginal band 12 of non-resilient material is left. It will be evident that a cushion filler which extended only between the edges of the overlasted margin is less comfortable 50 for the reason that it does not underlie the entire weight carrying area of the foot but tends to compact and leave a ridge that soon becomes noticeable to the wearer.

The invention is not confined to shoes which 55

are lasted with cement and have the soles cemented on but can be used with any of the usual combinations of methods of lasting and sole attaching. As shown in Fig. 5, an upper **33** may be lasted by using either staples **32**, tacks **34**, or pegs **36**. The sole **45** may be attached by a line of McKay or Littleway stitching as illustrated at **38**, or by pegs as shown at **40**.

It should be noted that it is important to gouge **10** the insole to a depth permitting a cushion filler of appreciable thickness to be employed. A cushion filler which is only equal in thickness to the thickness of the overlasted margin cannot serve the purpose of an effective cushion because its **15** thinness would not permit appreciable resiliency in the shoe.

Having thus disclosed my invention what I claim as new and desire to secure by Letters Patent of the United States is,

1. A shoe comprising an insole having its fore-

part recessed so as to provide a narrow marginal band of a width not exceeding the full thickness of the insole, resilient cushioning material filling said recess, an upper having its margin lasted over the band and an appreciable area of the exposed surface of the cushioning material, said upper being secured to the cushioning material, and an outsole attached to the shoe bottom.

2. A shoe comprising an insole having its fore-part recessed so as to provide a narrow marginal band of a width not exceeding the full thickness of the insole, resilient cushioning material filling said recess, an upper having its margin lasted over the band and an appreciable area of the exposed surface of the cushioning material, said upper being adhesively secured to the band and to the cushioning material, and an outsole attached to the shoe bottom.

JAMES C. GIVREN.
